[57] CLAIM

The ornamental design for a child's car seat, as shown and described.

DESCRIPTION

FIG. 1 is a front perspective view of a child's car seat showing my design;

FIG. 2 is a front elevational view of the seat shown in FIG. 1;

FIG. 3 is a left side elevational view of the seat shown in FIG. 1, identical in appearance to the right side view of the child's car seat;

FIG. 4 is a rear elevational view of the seat shown in FIG. 1; and

FIG. 5 is a bottom view of the seat as shown in FIG. 1.

FIG. 1

FIG. 2

FIG. 3

FIG. 4

FIG. 5
